(57) **CLAIM**

The ornamental design for a medical instrument, as shown and described.

DESCRIPTION

FIG. 1 is a bottom plan view of a medical instrument;
FIG. 2 is a top plan view thereof;
FIG. 3 is a right elevational view thereof;
FIG. 4 is a left elevational view thereof;
FIG. 5 is a back, upside down elevational view thereof; and,
FIG. 6 is a front elevational view thereof.
The broken lines adjacent to the claimed areas represent the bounds of the claimed design while all other broken lines are directed to environment and are for illustrative purposes only.
The broken lines form no part of the claimed design.
